ORNAMENTAL EAR CLIP

Margaret Barron, Brooklyn, N.Y.

Application April 25, 1947, Serial No. 743,763

1 Claim. (Cl. 63—14)

1.

This invention relates to ornamental ear clips. One object of the invention is to furnish an ornament unique in character in that it covers the major portion of the face of the external ear.

To the best of my knowledge, ear ornaments have heretofore been confined to earrings and ear clips connected to and limited to the area of the lobe of the ear. In many persons, the ear is often of unsightly configuration and in such cases is frequently concealed by the hair. However, I have perceived that added smartness and superior decorative effects could be obtained by the provision of an ornament whose configuration supersedes, as it were, the shape of the ear and thus provides at least partial concealment for the ear and ample space for ornamentation or virtually infinite variety. Preferably this decoration is somewhat longer than the external ear, and extends at least from the helix to the lobe of the ear, desirably in the form of a crescent or curve conforming at least approximately to the outer edge of the external ear.

It is therefore an object of the invention to provide an ear ornament of improved character having the novel features above mentioned. Another object of the invention is the provision of improved means for clipping the ornament to the ear in a manner affording a substantial degree of adjustability to ears of various shapes and contours, bearing in mind that the major portion of the external ear is rather sensitive to pressure, much more so than the lobe thereof.

Another object of the invention is to furnish such improved securing means whereby the device may be at least partially suspended over the helix of the ear and then frictionally engaged with the ear at a plurality of points therealong.

Other objects and advantages of the invention will become apparent as the specification proceeds.

With the aforesaid objects in view, the invention comprises the novel features, combinations and arrangements of parts hereinafter described in their preferred embodiments, pointed out in the subjoined claim, and illustrated in the annexed drawing, wherein like parts are designated by the same reference characters throughout the several views.

In the drawing:

Figure 1 is a view in front elevation showing an ornamental ear clip embodying the invention, with parts of the ear indicated in dotted lines.

Fig. 2 is a view in end elevation of the device.

Figs. 3 and 4 are similar views of different modifications.

2.

The advantages of the invention as here outlined are best realized when all of its features and instrumentalities are combined, but useful embodiments may be produced involving less than the whole.

It will be obvious to those skilled in the art to which the invention appertains, that the same may be incorporated in several different constructions. The accompanying drawing, therefore, is submitted merely as showing a preferred exemplification of the invention.

Referring in detail to the drawing, 10 denotes an ornamental ear clip embodying the invention. The same includes a decorative member 11 which may consist of a single piece of material of precious metal or the like, or it may include a series of wires 12 or other suitable sections adapted to carry the pendant pearl or other decorative articles 13. The details of construction involved in the member 11 are of no particular importance, and it suffices that this member constitute a unitary fairly rigid structure with the different sections cut out of a single sheet of metal or soldered or welded together, with the pendant mountings including links or the like if desired. Suffice it to say that the member 11 is approximately equal to the length of the external ear 14 herein shown in dotted lines and is preferably somewhat longer so that the upper part of the member 11 extends above the helix 15 of the ear while the lower part extends below the lobe 16 of the ear. In general, the shape of the member 11 is of curvilinear or crescent form, generally approximating the free edge or at least the helix of the ear. Thus the decorative member 11 is adapted to overlie and conceal the principal features and the shape and outline of the ear so that in effect the shape of the ornament supersedes that of the ear. While the decorative member 11 may lie in a plane, this is not essential the requisite being that it seat in a proper firm and flatwise manner against the front face of the ear, with such variations in shape as may be desired for additional securement or frictional contact with the ear.

In spaced relation to the decorative member 11 is the second part of the clip comprising an elongated element extending along the major portion of the length of the external ear and being in contact at a plurality of points with the rear face of the ear. The portion 18 forming a part of one of the elements 11 and 17 interconnects them to provide a seating portion engaging the helix 15 of the ear. In this way the weight of the device 10 is reliably carried. The wire ele-

ment 17 desirably consists of a highly flexible metal or the like having only a limited degree of resilience in the sense that the resilience is not as important as easy bendability to shape the element 17 to conform to the contour of the rear surface of the ear. The element 17 is shown as having some undulations which approximately correspond to the rear face of the ear. This element 17 may be curved according to the arc or crescent of the decorative member 11. In other words, it is principally the outer edge portion of the external ear which is clipped by the device 10. By providing a series of engagement points or areas, the device 10 is reliably held in position without undue pressure such as would cause discomfort to the sensitive part of the external ear. The element 17 may be bent in the store or by the purchaser herself to achieve the desired comfort. A feature of the instant construction is that the long wire element 17 is free at its lower end and extends at least down to and along the region of the rear surface of the antihelix of the ear, as is clear from Figs. 1 and 2.

In Fig. 3 is shown a modification according to which a wire element 17a is connected at 18a to the decorative member 11 at the outer edge of the latter. This connection 18a may be approximately central between the upper and lower ends of the element 17a. The ends of the latter are free for easy bending and complete flexibility, but the upper portion may be slightly bent at 19 to form a seat on the helix 15 in the same manner as was done by the part 18.

In Fig. 4 is shown a modification in which an element such as 17 is composed of a plurality of free ended sections 17b, the upper being connected at 20 and the lower at 21 to the decorative member 11. The parts 17b afford virtually a complete loop adapted to receive an appropriate portion of the ear, and nevertheless these parts may be bent to suit as hereinbefore described.

It will now be seen that I have provided a device which fulfills the objects of the invention and is well adapted for practical use.

I claim:

An ornamental ear clip for attaching against the front face of an external ear of a wearer comprising a decorative member extending from the helix to the lobe of the ear shaped approximately to conform with the edge contour of the free portion of said ear for resting flatwise on said front face, a flexible free-ended wire element extending along the region of the rear side of the antihelix of the ear when in effective position in approximately parallel relation to said decorative member and bent to conform to variations in the contour of said regional rear side, said element extending over the top of the ear helix and connecting with said decorative member substantially midway of the top portion thereof, the portion of said element extending over the helix adjacent said connection forming a seat for the ear clip spaced from the upper jointure of the ear and head, the major portion of said element including the free end thereof grippingly engaging the ear between the element and decorative member at a plurality of points along said antihelix region so constructed and arranged to solely retain the ear clip in said seated position.
